CANDLE LAMP

James E. Beckwith, New York, N. Y.

Application August 15, 1951, Serial No. 16,292

Term of patent 14 years

(Cl. D48—2)

To all whom it may concern:

Be it known that I, James E. Beckwith, a citizen of the United States and a resident of New York, in the county of New York, State of New York, have invented a new, original, and ornamental Design for a Candle Lamp, of which the following is a specification, reference being had to the accompanying drawing, forming a part hereof.

In the drawing,

Figure 1 is a side elevational view of a candle lamp showing my new design; Figure 2 is a top plan view thereof; and Figure 3 is a view taken along line 3—3 of Figure 1 on a reduced scale.

I claim:

The ornamental design for a candle lamp, substantially as shown.

JAMES E. BECKWITH.
